GOLF PUTTER

Vance V. Elkins, Jr., 42 Hampton Drive,
Freehold, N.J. 07728

Filed June 25, 1971, Ser. No. 157,082

Term of patent 14 years

Int. Cl. D21—02

U.S. Cl. D34—5

FIG. 1 is a front perspective view of a golf putter showing my new design;

FIG. 2 is a left side view thereof;

FIG. 3 is a rear view thereof;

FIG. 4 is a top view thereof; and

FIG. 5 is a bottom view thereof.

I claim:

The ornamental design for a golf putter, substantially as shown.
